UNITED STATES PATENT OFFICE.

JAMES T. ANDREW, OF MONTGOMERY, ALABAMA.

SAFETY APPLIANCE ESPECIALLY ADAPTED FOR LOCOMOTIVES.

1,056,724.

Specification of Letters Patent.

Patented Mar. 18, 1913.

Application filed January 11, 1913. Serial No. 741,543.

To all whom it may concern:

Be it known that I, JAMES T. ANDREW, a citizen of the United States, residing at Montgomery, in the county of Montgomery and State of Alabama, have invented certain new and useful Improvements in Safety Appliances Especially Adapted for Locomotives; and I do hereby declare the following to be a full, clear, and exact description 10 of the invention, such as will enable others skilled in the art to which it appertains to make and use the same.

This invention relates to railway safety appliances, and has for its object to produce 15 a device of this nature which will be especially applicable to locomotives, and will serve to prevent the same from leaving the track when accidents are met with which would ordinarily cause disastrous results.

With this and other objects in view, the invention consists in the novel details of construction and combinations of parts more 20 fully hereinafter disclosed and particularly pointed out in the claims.

Referring to the accompanying drawings forming a part of this specification in which like numerals designate like parts in all the views:—Figure 1 is a diagrammatic elevational view of a portion of the framework 25 supporting a locomotive and its coacting parts, with my attachment applied thereto; Fig. 2 is a diagrammatic cross sectional view of a portion of the parts shown in Fig. 1; and, Fig. 3 is an elevational view in perspective of a special chair or casting employed 30 to connect my attachment to the framework of the locomotive.

1 indicates the usual wheels and drivers of the modern locomotive; 2 a portion of the 35 framework thereof comprising the longitudinal bars 3 and 4; 5 the axle of the drivers 1; 6 the brake shoes applied to said drivers; and 7 the brake beams for supporting said shoes.

8 represents a casting preferably of the shape shown in Fig. 3, and provided with the lugs 9 and 10 forming the channel 11^a therebetween, as well as the lug 11 coacting with the base portion 12 forming the channel 50 13 therebetween. The frame member 3 is adapted to fit the channel 11^a, and suitable bolts 14 are passed through the holes 15 in order to secure said frame portion 3 in said channel 11^a. Like bolts may be passed 55 through the holes 16 in order to secure the frame member 4 in the channel 13, where-

upon the whole casting 8 will be firmly secured to the engine frame. In order to supply additional bracing means, I have further provided the bent rods 20 which pass 60 through lugs 21 secured to the frame member 4 and pass over lugs 22 secured to the frame member 3, all as will be clear from Fig. 1. The cast or forged supporting members 8 are preferably located between the 65 framework 3 and 4, and the said bent rods 20, as indicated in Fig. 1. The said members 8 are provided with the sector shaped openings 25 into which fit the cylindrically shaped supporting members 26 extending 70 underneath the engine frame from side to side and from say six or eight inches beyond the drivers 1. The said members 26 are provided inside the members 8 with the collars 27 which may be secured to said members 75 26 in any suitable manner, as by the pins 28. The said members 27 are provided with flanges 29 located about six or eight inches inside the flanges 30 of the drivers 1, and the parts are so located and proportioned 80 that the under surface 31 of the said members 26 will rest a short distance above the top surface 32 of the rails 33. The said cylindrical supporting members 26 are loosely fitted in the sector shaped openings 85 25, so that they may freely rotate therein when their outer surfaces 31 are brought into contact with the top surfaces 32 of the rails 33.

The operation of my improved safety device for locomotives will be clear from the foregoing, but may be briefly summarized as follows:—Should the locomotive leave the track for any cause, say on the right hand side of the rails, as seen in Fig. 2, then 90 the extending portion of the supporting members 26 will contact with the rail 32, on the left of Fig. 2, and the portion of the said member 26 between the driver 1 and the collar 27 on the right of Fig. 2, will contact 95 with its corresponding rail, so that the locomotive will still be supported by the said members 26. The momentum of the locomotive, of course, will carry it along a certain distance, and the said members 26 will rotate in their bearings 25, until the engine is 100 stopped either through the friction engendered, or preferably by the automatic application of the air brakes, in a manner not illustrated in this case, but fully disclosed 105 in my prior patents relating to the same general subject.

An important feature of the present construction resides in the fact that by supporting the members 26 on the chairs or supporting members 8, I am enabled to readily apply my improvement to modern engines without reorganizing or interfering with the present construction of their frameworks and coacting parts. It is especially important that the said members 8 are of the U-shape shown, in order that the brake beams 7 may be readily accommodated between the drivers, as well as my supporting members 26.

It is obvious that those skilled in the art may vary the arrangement of parts as well as the details of construction, without departing from the spirit of my invention, and therefore, I do not wish to be limited to the above disclosures, except as may be required by the claims.

What I claim is:—

1. In a railway safety appliance, the combination of a supporting frame; wheels associated with said frame; supporting chairs provided with slots located between the axles of said wheels; brake beams passing through said slots; and supporting members adapted to contact with the rails in case of accident, carried by said chairs, substantially as described.

2. In a railway safety appliance, the combination of a supporting frame; wheels associated with said frame; supporting chairs provided with channels fitting said frame and with slots located between the axles of said wheels; brake beams passing through said slots; and supporting members extending beyond said wheels adapted to contact with the rails in case of accident, carried by said chairs, substantially as described.

3. In a railway safety appliance, the combination of a locomotive provided with a

frame and a plurality of drivers mounted on axles; a channeled supporting chair secured to said frame between a pair of said axles and provided with an opening; a brake beam passing through said opening; means comprising lugs on said frame for bracing said chair; and a supporting member carried by said chair adapted to contact with the rail in case of accident, substantially as described.

4. In a railway safety appliance, the combination of a locomotive provided with a frame, and a plurality of drivers mounted on axles; a supporting chair provided with channels secured to said frame between a pair of said axles and provided with an opening; a brake beam passing through said opening; means comprising lugs on said frame and a bent rod secured to said lugs for bracing said chair; and a supporting rotating member carried by said chair adapted to contact with the rail in case of accident, substantially as described.

5. In a railway safety appliance, the combination of a locomotive provided with a frame, and a plurality of drivers mounted on axles; a supporting chair secured to said frame between a pair of said axles and provided with an opening; a brake beam passing through said opening; means comprising lugs on said frame for bracing said chair; and a supporting member carried by said chair extending under said frame and beyond said drivers at each side and adapted to contact with the rail in case of accident, substantially as described.

In testimony whereof, I affix my signature, in presence of two witnesses.

JAMES T. ANDREW.
